SELF SHARPENING DIPPER TOOTH

Filed Aug. 27, 1931

Fig. 3.

Inventor,

John C. Taylor, Jr.

By *Jaet. Richmond*

Attorney

UNITED STATES PATENT OFFICE

JOHN C. TAYLOR, JR., OF EASTON, PENNSYLVANIA, ASSIGNOR TO TAYLOR WHARTON IRON AND STEEL COMPANY, OF HIGH BRIDGE, NEW JERSEY, A CORPORATION OF NEW JERSEY

SELF-SHARPENING DIPPER TOOTH

Application filed August 27, 1931. Serial No. 559,781.

Digging teeth or so-called dipper teeth suffer more or less rapid wear in service and for economical reasons it has been standard practice for many years to make the point 5 separate from the base so that it can be reversed after one side is badly worn and so that it can be replaced eventually when it has outlived its usefulness. The point being of wedge form, the effect of wear is to increase 10 its digging section so that, notwithstanding reversal from time to time, it becomes too blunt for effective digging and consequently, must be replaced.

The object of my invention is to prolong 15 the useful life of points of dipper teeth by constructing them so that they will be self-sharpening and will always present an effective digging edge notwithstanding progressive increment of section.

20 The nature of the invention consists in so constructing the point as to provide a potential area of division, as by indentation, grooving, recessing, or channeling, medially of the cutting edge and which becomes more and 25 more defined with progressive increase of point section thereby to overcome the ordinary condition of bluntness of section by establishing twin or multiple cutting points, as, for example, by constructing a point with 30 a cored area extending from its apex rearwardly to or near the region of the web or shank, for the purpose and with the result of providing for self-sharpening of the point in service.

35 One embodiment of the invention is shown in the accompanying drawings forming a part hereof, wherein

40 Figure 1 is a perspective view of a point having self-sharpening capacity in accordance with my invention.

Fig. 2 is a central longitudinal sectional view of the same.

Fig. 3 is a section on line 3—3 of Fig. 2.

45 Fig. 4 is a perspective view illustrative of a tooth which has sharpened itself in service.

Except as hereinafter noted the dipper tooth both as regards point and base, is or may be as usual. According to my invention the point 5 is constructed, either in the act of 50 casting or otherwise, with a medial cored area

6 extending from its apex rearwardly to, or in the region of the web or shank 7, for the purpose and with the result of providing for self-sharpening of the point in service.

A point of this type, before service, would 55 have a slight groove or indentation 8 which would become more and more defined with increase of point section so as to result in the condition shown in Fig. 4, which represents how, notwithstanding, increment of digging 60 section, the indenting, grooving, or division of the cutting edge becomes more pronounced as the wear makes for larger section. The described self-sharpening action of the new tooth results in the establishment of twin cut- 65 ting edges 9.

Whether the section of the cored area be 70 circular, polygonal or a compromise thereof, is of no particular importance although it is perhaps easier to use the circular cross section shown in the drawings. In any event, I prefer to increase the cross-sectional area in a direction rearwardly of the point, that is to say, in conformity with increase of digging 75 section. The effect of this is to accentuate the line of parting of the digging edge or, in short, to promote the self-sharpening capacity of the point. And as before intimated, the cored area may extend from or immediately back of the apex of the point to or with- 80 in the region of the web or shank. So far as concerns the principle of self-sharpening it would be sufficient to have the cored area stop short of the rear wall of the point. On the other hand by having it extend to the clear 85 there might be some advantage in the heat treatment of points of relatively large section.

Having described my invention, I claim:—

1. A digging tooth having a point formed internally with a recess ranging rearwardly of its cutting edge, whereby the cutting edge is divided in response to wear to overcome bluntness.

2. A digging tooth having a point formed with an axial recess effective to establish multiple digging edges in response to wear.

3. A digging tooth having a point formed with a recess that opens into the cutting edge 100 to overcome bluntness in response to wear.

4. A digging tooth having a point whereof the cutting edge is formed with an indentation and whereof the body has a cored portion coextensive with said indentation.
5. A digging tooth having a point, the cutting edge of which is grooved or indented, the back wall of the groove having a recess extending longitudinally into the body.
6. A digging tooth having a point of conventional wedge form, and an axial cored portion in the path of wear and effective to establish apical rugosities in response to wear.
7. A digging tooth having a point of conventional wedge form with a cored portion ranging axially thereof, whose cross sectional area increases in conformity with increase of digging section.
8. A self-sharpening digging tooth having a point of conventional wedge form whereof the cutting edge is grooved, the back wall of the groove having a tubular opening extending the effective length of the point.
9. A digging tooth of the solid wedge form having a central cavity substantially the depth thereof and effective to divide the point to overcome the usual bluntness following wear.

In testimony whereof, I affix my signature.

JOHN C. TAYLOR, JR.
